UNITED STATES PATENT OFFICE

96,387

DESIGN FOR A DOILY

Robert J. Hutt and George A. Hutt, Brooklyn,
N. Y., assignors to U. S. Lace Paper Works,
Inc., Brooklyn, N. Y.

Application April 29, 1935, Serial No. 56,622

Term of patent 3½ years

To all whom it may concern:

Be it known that we, Robert J. Hutt and George A. Hutt, citizens of the United States and residents of Brooklyn, in the county of Kings and State of New York, have invented a new, original, and ornamental Design for Doilies, of which the following is a specification, reference being had to the accompanying drawing, forming part thereof.

The figure of the drawing is a plan view of the doily showing one-quarter section of the design in detail, which design continues throughout the extent of the doily as indicated by the extension of the outline of the doily in dotted lines.

We claim:

The ornamental design for a doily as shown and described.

ROBERT J. HUTT.
